(57) **CLAIM**

The ornamental design for a deflector for fire protection sprinkler, as shown and described.

DESCRIPTION

FIG. 1 is a front perspective view of a deflector for fire protection sprinkler (the dashed lines are for illustrative purposes only and do not form part of the invention);

FIG. 2 is a top view thereof (the bottom view is identical to the top view; the dashed lines are for illustrative purposes only and do not form part of the invention);

FIG. 3 is a front view thereof (the back view is identical to the front view); and,

FIG. 4 is a right side view thereof (the left side view is identical to the right side view).
